CLAIM

The ornamental design for a pizza slice container as shown and described.

DESCRIPTION

FIG. 1 is a first front perspective view of a pizza slice container in an open state showing my new design;
FIG. 2 is a second front perspective view thereof;
FIG. 3 is a third front prereview view, the container in a closed state;

FIG. 4 is a front view of FIG. 1;

FIG. 5 is a rear view of FIG. 1; and,

FIG. 6 is a left side of FIG. 2, the right-side view being a mirror image thereof.

The broken lines showing of a pizza in FIG. 2 is included for the purpose of illustrating environmental structure and forms no part of the claimed design.
